UNITED STATES PATENT OFFICE

MARY C. McCARVILLE, OF ARCADIA, CALIFORNIA

COVER AND POLISHER DEVICE FOR BROOMS

Application filed July 29, 1930. Serial No. 471,477.

This invention relates to a cover and polisher device for brooms, and it is an object of the invention to provide a device of this kind comprising two members, one of which when applied entirely enclosing the head of a broom or the like while the second member when applied is disposed over the first member.

The invention consists in the details of construction and in the combination and arrangement of the several parts of my improved cover and polisher device for brooms whereby certain important advantages are attained and the device rendered simpler, less expensive and otherwise more convenient and advantageous for use, as will be herein-after more fully set forth.

The novel features of my invention will hereinafter be definitely claimed.

In order that my invention may be the better understood, I will now proceed to describe the same with reference to the accompanying drawings, wherein:—

Figure 1 is a view in elevation illustrating a cover and polisher device constructed in accordance with an embodiment of my invention and in applied position, a portion being broken away;

Figure 2 is a fragmentary view illustrating a detail comprised in the construction of the polisher member;

Figure 3 is a fragmentary view illustrating a detail of construction comprised in the polisher member;

Figure 4 is an elevational view of the cover member in applied position;

Figure 5 is an elevational view of the cover member partly in applied position;

Figure 6 is a fragmentary view in perspective of the end portion of the cover member coacting with the handle end of the broom head.

My improved cover and polisher device as herein disclosed comprises two members A and B, the member A constituting a cover for a broom head or the like and the member B constituting the polisher proper.

The member A is made of linen cloth or the like formed to provide an elongated tubular member, one end of which being formed

to provide a casing or sheath 1 through which is directed a gathering cord 2, the wall of the casing or sheath 1 is provided with a suitable opening 3 through which a portion of the cord is directed. The cord 2 is preferably continuous and upon requisite pull being imposed thereon the end of the cover member A provided with the casing or sheath 1 is gathered or contracted to assure the proper fitting of the cover member upon a broom head or the like as particularly illustrated in the accompanying drawings. In other words, this end of the cover member A is contracted or gathered to substantially closely engage around the handle member H of the broom or the like. To facilitate the desired maintenance of this end portion of the member A in its gathered or contracted adjustment I provide the cord 2 at desired points therealong with the conventional separable fasteners 4 preferably of a resilient head and socket type.

When these separable fasteners 4 are in connected or locked arrangement expansion of the gathered end of the member A is prevented.

The member A is of a length materially in excess of the length of the broom head and after being initially applied to the broom head as illustrated in Figure 5, the side portions of that part of the member A positioned beyond the broom head are turned or folded inwardly, as at 5, with the overlapping portions of the free corners of the member A having interlocking separable fasteners 6 also preferably of a resilient head and socket type. When these fasteners 6 are engaged the side portions of the extended part of the member A are locked in such arrangement. Inwardly of its sides the end portion of the member A carrying the separable fasteners 6 also carry the separable fasteners 7 which, when the extended portion of the member A is folded to overlie the broom head proper, interlock with the coacting separable fasteners 8 suitably positioned upon the member A at a point in relatively close proximity to the end of the member A provided with the casing or sheath 1. In this end of the cover member A a wall thereof

is provided with an extended portion or flap 9 provided at substantially the transverse center of the member A with a separable fastener member 10 for locking engagement with a separable fastener member 11 positioned intermediate the fasteners 8 hereinbefore referred to and in transverse alignment therewith.

Through the instrumentality of the coacting fastening members 7 and 8 and 10 and 11 the cover member A is held to a broom head in a manner to effectively enclose the same and with the liability of accidental displacement substantially eliminated. At the same time this member A when desired can be readily and conveniently removed.

The polisher member B is preferably made of silk cloth and comprises a tubular member provided at one end with a sheath or casing 12 through which is threaded a continuous strip 14, said strip 14 coacting with the sheath or casing 12 to gather or contract one end portion of the member B so that the same may effectively coact with the handle member H of the broom and also be properly arranged over the broom head and the cover member A applied thereto. The casing or sheath 12 at desired points therearound has secured thereto the loops or eye members 15 which provide efficient means to facilitate the removal of the polisher device from applied position and particularly along the handle member H.

The member B gradually flares outwardly from said contracted or gathered end toward the opposite end, and at a predetermined point inwardly of said opposite end the wall of the member B is provided therearound with a flounce 16 maintained by the internally arranged tapes 17 suitably stitched to the member B proper.

With the member A applied to the broom head, the member B may be effectively employed in household work as a polishing member without liability of injury to the surfaces being treated. It is to be further stated that the efficiency of the polishing operation is materially increased in view of the fact that the cover member A is so applied to the broom head to permit said broom head freedom of movement. While I have hereinbefore particularly referred to my invention as being employed in connection with a broom head, I wish to state that it can be used with equal advantage in connection with a whisk broom or kindred brushing element.

From the foregoing description it is thought to be obvious that a cover and polisher device for brooms constructed in accordance with my invention is particularly well adapted for use by reason of the convenience and facility with which it may be assembled and employed, and it will also be obvious that my invention is susceptible of some change and modification without departing from the

principles and spirit thereof and for this reason I do not wish to be understood as limiting myself to the precise arrangement and formation of the several parts herein shown in carrying out my invention in practice except as hereinafter claimed.

I claim:

A cover member for a brush head comprising a tubular member of a length greater than the length of the brush head, means for contracting one end portion of the member, the opposite end portion of the cover member having coacting locking means for holding side portions of the cover member folded, and locking means carried by said side portions of the cover member and the cover member in relatively close proximity to its contracted end, said last named locking means coacting when the cover member is folded along a line transversely thereof.

In testimony whereof I hereunto affix my signature.

MARY C. McCARVILLE.
